UNITED STATES PATENT OFFICE.

GUSTAVUS NORGRAN, OF CENTERVILLE, SOUTH DAKOTA.

CORN-HUSKING MACHINE.

1,422,609.

Specification of Letters Patent. Patented July 11, 1922.

Application filed December 21, 1920. Serial No. 432,282.

To all whom it may concern:

Be it known that I, GUSTAVUS NORGRAN, a citizen of the United States of America, residing at Centerville, in the county of Turner 5 and State of South Dakota, have invented new and useful Improvements in Corn-Husking Machines, of which the following is a specification.

The object of the invention is to provide 10 a simple and efficient apparatus for uniformly and expeditiously stripping the husks from ears of corn as they are harvested to avoid the loss of time and inconvenience incident to performing the operation manually and at the same time insure a commercial product without requiring special 15 attention in the course of the operation upon the part of the attendant, and to this end, and more particularly to provide means in 20 connection with the device by which the ears are fed to the husking rolls or equivalent elements, for positioning said ears so that an effective operation of the husking elements is assured; and with this object in view 25 the invention consists in a construction and combination of parts of which a preferred embodiment is shown in the accompanying drawings, wherein:—

Figure 1 is a side view of a husking apparatus embodying the invention.

Figure 2 is a front view of the same.

Figure 3 is a rear view.

Figure 4 is a detail plan view to show the means by which motion is communicated 35 to the husking rolls.

The apparatus consists essentially of an elevator 10 which is in communication at its lower or receiving end with a hopper 11 suitable to facilitate the dumping of the ears 40 of corn as they are brought from the field, a series of pairs of husking rolls 12 disposed at a downward inclination from their receiving toward their delivery ends, their receiving ends being disposed adjacent to the delivery 45 end of the elevator and the pairs of husking rolls being arranged in separate compartments or chutes between which are arranged division walls 13, between which the ears are 50 adapted to be received in longitudinally progressive positions in substantial parallelism with the husking rolls, to the end that an effective engagement of the rolls with the husks may be assured, and ear positioning means arranged in operative relation with 55 the elevator for disposing the ears as they are carried by the elevator toward the receiv-

ing ends of the husking rolls to enter said chutes in the desired relation thereto.

In the construction illustrated the elevator consists of a chute 14 traversed by an 60 apron or belt 15 having suitable flights or spurs 16 for engaging the ears of corn and removing them in a more or less continuous series or layer from the hopper, and located above the elevator apron or belt and in trans- 65 verse relation thereto preferably adjacent to the upper end of the elevator is a drum 17 provided with a series of radial fingers 18 which terminally operate during the rotation of the drum adjacent to the surface of the 70 apron or belt so as to engage the ears of corn as they are carried upward by the latter, rotary motion being communicated to the drum through a chain 19 extending from a sprocket wheel 20 carried by a transverse 75 countershaft 21 which in turn receives its motion through a chain 22 from the drive shaft 23. The elevator apron or belt also receives motion from the countershaft 21 and hence the drum 17 is rotated in reverse di- 80 rection to the apron so that the fingers 18 move rearwardly or against the direction of movement of the ears and tend to retard their movement under the influence of the 85 apron or belt and prevent them from passing the drum except when longitudinally aligned with the apron or in other words unless arranged in an end-wise relation or in a position to progress longitudinally so that they 90 respectively enter the husking chutes be- 90 tween the partition or division walls 13 in substantial parallelism with the husking rolls and thus are presented in the proper position to have their husks engaged by 95 said rolls and effectively removed in their downward movement toward the delivery ends of said rolls. The husked ears are 100 discharged from the rolls upon a delivery table 24 from which they may be deposited in any suitable receptacle, not shown, while the husks drop into a hopper 25 located beneath the husking rolls, said hopper having an inclined concentrating bottom 26 serving to direct the husks to the lower end of a discharge conveyor 27 driven through a shaft 105 28 receiving motion from a chain 29 actuated by the drive shaft. The upper ends of the partition walls 13 at the receiving end of the husking chutes are covered by a transverse inclined fender 30 serving to prevent the 110 ears from being thrown outside of or beyond the husking chutes in the event that for

any reason they should become caught or turned over in their passage from the upper end of the feed elevator 10 to the husking chutes.

5 Having described the invention, what is claimed as new and useful is:—

1. A corn husking apparatus having an ear feeding mechanism provided with an endless apron or belt, husking mechanisms 10 having chutes for receiving the ears in end-wise progressive position, and ear positioning means located adjacent to the delivery end of the feed mechanism for disposing the ears in parallelism with the direction of 15 progress, said positioning means consisting of a rotary drum disposed axially in transverse relation to the movement of the apron of the feed mechanism and provided with fingers for engaging the ears carried by said 20 apron.

2. A corn husking apparatus having an ear feeding mechanism provided with an endless apron or belt, husking mechanism having chutes for receiving the ears in end-wise progressive position, and ear positioning means located adjacent to the delivery end of the feed mechanism for disposing the ears in parallelism with the direction of 25 progress, said positioning means consisting of a rotary drum disposed axially in transverse relation to the movement of the apron of the feed mechanism and provided with fingers for engaging the ears carried by said 30 apron, said drum being revoluble in a direction reverse to the movement of the apron.

3. A corn husking apparatus having an ear feeding mechanism provided with an endless apron or belt, husking mechanism having chutes for receiving the ears in end-wise progressive position, and ear position- 40

ing means located adjacent to the delivery end of the feed mechanism for disposing the ears in parallelism with the direction of progress, the positioning means having ear engaging fingers for traversing the surface 45 of the apron of said feed mechanism.

4. A corn husking apparatus having an ear feeding mechanism provided with an endless apron or belt, husking mechanism having chutes for receiving the ears in end-wise progressive position, and ear positioning means located adjacent to the delivery end of the feed mechanism for disposing the ears in parallelism with the direction of 50 progress, the positioning means having ear engaging fingers for traversing the surface of the apron of said feed mechanism and means for moving said fingers in a direction opposite to that of the progress of said 55 apron.

5. A corn husking apparatus having an ear feeding mechanism provided with an endless apron or belt, husking mechanism having chutes for receiving the ears in end-wise progressive position, and ear positioning means located adjacent to the delivery end of the feed mechanism for disposing the ears in parallelism with the direction of 60 progress, the feed mechanism and husking mechanism having their apron and chutes 65 respectively inclined upward and downward, toward and from their communicating delivery and receiving ends, and an inclined fender being disposed transversely adjacent to said communicating ends of the 70 feed and husking mechanisms.

In testimony whereof he affixes his signature.

GUSTAVUS NORGREN.
